UNITED STATES PATENT OFFICE.

WILLIAM W. LYITLE, OF SEATTLE, WASHINGTON, ASSIGNOR OF ONE-HALF TO ROBERT S. MAUS, OF SEATTLE, WASHINGTON.

BARREL.

No. 926,502.

Specification of Letters Patent.

Patented June 29, 1909.

Application filed July 24, 1908. Serial No. 445,176.

To all whom it may concern:

Be it known that I, WILLIAM W. LYITLE, a citizen of the United States, residing at Seattle, in the county of King and State of Washington, have invented certain new and useful Improvements in Barrels, of which the following is a specification.

This invention relates to improvements in barrels, and its object is the provision of means whereby the manufacture of barrels is simplified and the cost of production correspondingly lessened.

The invention consists in a barrel which is constructed of one or more staves provided with crozes, and having heads which are reliably held in place through the medium of stirrups, as will be hereinafter particularly described and claimed.

In the drawings, Figure 1 is a vertical cross-sectional view of a barrel constructed in accordance with my invention; and Fig. 2 is a perspective view of a barrel-stirrup, shown detached.

The reference numeral 5 designates the heads; and 6, the staves, which are bound by hoops 7 to form a barrel. The heads are each desirably constructed of wood, as shown in the drawing, and which may advantageously be disposed to have the grain of the respective layers of a head rectangular to each other. To secure the heads in place, I employ a plurality of metallic fastening devices, each of which consists of a shank 8 which is bent at 9 and 10 to provide two lateral and oppositely directed portions 11 and 12, which, in turn, are respectively bent at 13 and 14 to provide oppositely directed portions 15 and 16 which are approximately parallel to the aforesaid shank, and affording a stirrup having two reversely arranged hooks, as best shown in Fig. 2. The stirrup parts 15 terminate in points 17.

In application, a head is pierced in proximity of its periphery, as at 18, and at a distance from the head margin of about the length of the fastening part 11. Within the holes thus formed the parts 15 are inserted from the inner faces of a head, and the projecting points 17 are then turned over and driven back into the wood as at 19 to provide clenches to securely hold the fastenings to the head. The head thus armed with hooks extending radially from its periphery is inserted within the end of the barrel so that the hooks will catch over the ends of the staves, see Fig. 1, and firmly secured by a barrel-hoop being nailed over the stirrup-parts 16. By such devices the head is securely held in place against being driven either inwardly or outwardly.

What I claim, is—

1. In a barrel, the combination with the staves and a head, of stirrups adapted to hook over the ends of said staves and extending below the head having a part which is passed through the head and clenched upon the outer face of the head.

2. In a barrel, the combination with the staves and a head formed of two thicknesses of material, of stirrups adapted to hook over the ends of said staves and extending below the head having a part which is passed through the head and clenched upon the outer face of the head, and a hoop for retaining the stirrup hooks in engaged position with said staves.

In testimony whereof, I affix my signature in the presence of two witnesses.

WILLIAM W. LYITLE.
